(57) CLAIM

The ornamental design for a headwear holder, as shown and described.

DESCRIPTION

FIG. 1 is a perspective view of a headwear holder showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a second perspective view thereof, shown in an environmental state; and,

FIG. 9 is a third perspective view thereof, shown in a second environmental state.

The broken lines represent unclaimed subject matter and form no part of the claimed design.

1 Claim, 8 Drawing Sheets
